UNITED STATES PATENT OFFICE.

WALTER H. D'ARDENNE, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

PUNCHING MACHINE.

Application filed August 12, 1920. Serial No. 403,019.

To all whom it may concern:

Be it known that I, WALTER H. D'ARDENNE, residing at Philadelphia, Pennsylvania, have invented certain new and useful Improvements in Punching Machines, of which I declare the following to be a full, clear, and exact description.

This invention relates to punching machines.

10 One of the objects of my invention is to provide a punching machine which is simple in structure and efficient in operation.

15 A further object of the invention is to provide a machine of the character referred to wherein a plurality of punches may be operated simultaneously.

20 A further object is to provide a punching machine in which punches disposed and operating in relatively different planes are simultaneously actuated to produce holes in the work to be punched at relatively different distances from a given fixed plane.

25 A further object is to provide means in a machine of the nature referred to for efficiently supporting, centering and clamping the work.

Other objects of the invention will appear more fully hereinafter.

30 The invention consists substantially in the construction, combination, location and relative arrangement of parts, all as will be more fully hereinafter set forth, as illustrated in the accompanying drawings, and finally pointed out in the appended claims.

35 Referring to the drawings,—

Fig. I is a view in top plan of a machine embodying my invention showing a portion of the work to be punched arranged in working position in the machine, part of the 40 work being broken away to show one set or gang of punches;

Fig. II is a view in side elevation of the machine illustrated in Fig. I;

45 Fig. III is a view in vertical section on the line III—III, Fig. II, looking in the direction of the arrows, and showing the work-holding clamps in clamping position on the work, and the punches advanced;

50 Fig. IV is a view similar to Fig. III showing the work-holding clamps raised from the work and the punches retracted; and

Fig. V is a detail view in section on the line V—V, Fig. II, looking in the direction of the arrows, and showing details of a form

of clutch mechanism employed in connection with my invention.

The same part is indicated by the same reference numeral wherever it occurs throughout the several views.

55 In the manufacture of various structures out of sheet metal, such, for example, as automobile bodies, it is frequently necessary for various uses and purposes, to punch holes in the sheet metal panels or stampings employed, or in the edge flanges thereof. 60 Where the stamping or panel is of irregular contour or shape, as, for example, in the case of the side panels for automobile bodies, and the inturned flanges thereof at the door openings, due to the curvature of such 65 panels to conform to the contour and lines of the body, it frequently is necessary to punch or otherwise produce holes in one portion or flange of the stamping or panel which lie in a different plane from those 70 punched or formed in the other flange or another portion of the stamping or panel. In the case of flanged panels or stampings 75 of an automobile body structure, for illustration, due to the curvature of the panels or stampings, the flange at one edge, in which holes are to be formed, lies at one 80 distance from a fixed plane, for instance, the plane of the base of the work support, while the flange at the other edge of such 85 stamping or panel lies at a different distance from such plane.

80 Heretofore it has been a common practice to form the holes in sheet steel stampings or panels one at a time, particularly where the 90 holes are to be formed in relatively different planes as above defined, that is, in stampings or panels of curved or irregular shape and contour. This practice is not only slow and tedious, but is costly due to the necessary repeated handling of the stampings in presenting the same to the punches or drills, the breakage of drills and punches, and the time required to complete the work on each stamping or panel, thereby materially adding to the cost of the completed structure in which the stampings are to be employed. 95 In the case of an automobile body, for instance, the cost of construction according to the common practice is very substantially 100 increased.

105 It is among the special purposes of the present invention to provide a punching ma-

chine which will enable a plurality of holes or openings to be made simultaneously in sheet metal stampings or panels even where the holes are to be formed in portions of the panels or stampings which lie out of the same plane with respect to each other, thereby enabling the work of forming the holes or openings to be accomplished expeditiously, thereby reducing the time and cost.

10 In the accompanying drawings I have shown my invention as applied to the forming of holes or openings in sheet metal stampings or panels employed in the construction of automobile bodies, and particularly in this instance in the edge flanges of such panels or stampings where the holes or openings are to be formed at different distances from the plane defined by the base portion of the support upon which the stampings are carried while the holes or openings are being formed therein. It is to be understood, however, that my invention is not to be limited or restricted with respect to the use to which the stampings or panels are 25 to be employed.

In the arrangement shown, the panel is indicated at A. As clearly indicated in Figs. I, III and IV, the panel is formed with edge flanges, the holes or openings being formed in the said flanges, and the said panel or stamping is transversely inclined or curved so that the edges of the panel do not lie in the same plane. The panel to be punched may be supported in any suitable or convenient way. A simple arrangement is shown wherein at the point where the punching operations are carried on the panel rests upon a work support or bed 80 carrying dies 81 over which the respective edge flanges of the panel engage, said dies being at relatively different distances from the plane of the base of the support 80. In order to support the stamping in position upon the work bed or support 80 and the flanges thereof respectively engaging over the dies 81 I provide suitable work supporting members 46, 54, suitably secured to a vertically extending standard 42 of the machine frame work, as indicated at 47. The work supporting arms 46, 54, may be braced, if desired, by the braces 51, 58, mounted at convenient points upon the frame work, as indicated at 52, and connected at their outer ends to the outer portions of the work supporting arms 46, 54, as indicated at 53. The extremities 49, 56, of the supporting arms 46, 54, are formed with gauge stops 50 57, upon which the extremities of the stamping are supported in position. For certain 60 classes of stampings to be punched it is desirable to form the supporting arms with downwardly inclined portions as indicated at 48, 55, to conform to the shape of the stampings.

65 In the arrangement shown, a work sup-

porting arm is disposed at each side of the machine in order to accommodate both right hand and left hand panels or stampings, the work being presented to the action of the punching devices from one side or the other of the machine according to whether it is a right or left hand panel.

Cooperating with the dies 81 are the punches indicated at 79. These are carried in blocks 78 which are mounted to slide in suitable ways formed in the frame work of the machine. These punches may be advanced to their work or withdrawn therefrom in many different ways. A simple arrangement for this purpose is shown 80 wherein toggle links 72, 76, are pivotally connected together as indicated at 74 at their proximate ends, one of said links being pivotally connected to a slide block 78, and the other being pivotally connected as 85 at 73 to a fixed projection 78 forming part of the framework. Rock levers 64 are pivotally connected to the pivot pins 74 of the toggle links through link connections 75, which are pivotally connected as at 77, 90 to said rock levers. These rock levers are pivotally suspended as at 67 upon links 66 which are pivotally mounted upon portions 44 of the frame work of the machine. The other ends of levers 64 are pivotally connected as at 65 to a slide block 63 mounted to slide in fixed ways 43.

It is desirable to clamp and hold the panel or stamping firmly in position upon the work support 80 during the operation of the punches. Various constructions of clamp devices for this purpose may be employed. A simple arrangement is shown wherein clamping feet 85 carrying suitable clamp pads 88 are adjustably mounted in a member 84 pivotally mounted as at 83 upon a fixed part of the frame work. A desirable adjustment of the clamping feet may be secured by means of the lock nuts 87 engaging the threaded ends of the shanks 86 of the clamp feet. The members 84 may be rocked in any suitable or convenient manner into position for the clamping feet or the pads carried thereby to engage and efficiently hold the stampings in position, and also to be rocked or swung out of clamping position. A simple arrangement is shown wherein a lever 91 is pivotally mounted as at 90 in fixed portion 82 of the frame work, and is connected as at 92 115 to a link 93, which in turn is pivotally connected to the member 84. By this arrangement, by suitably manipulating the levers 91 the clamp devices may be quickly applied to or retracted from the work.

In the case of certain stampings, it is sometimes customary to form or press a bead therein as indicated at A'. In such cases it is desirable to employ a gauge bar indicated at 89 and carried by the clamping 120 130

devices to engage against the edge of the bead when the clamping devices are in clamping position, thereby insuring the proper positioning of the stamping for the holes 5 to be punched at the proper distances.

Any suitable arrangement for rocking the power actuated levers 64 may be employed. A simple arrangement is shown, to which, however, I do not desire to be limited or 10 restricted, wherein, as above described, the ends of said rock levers are pivotally connected to the slide block 63. To this slide block is connected a pitman 62 which is pivotally connected as at 61 to an eccentric pin 15 carried by a disk or wheel member 59, see Fig. I. This wheel or disk may be power driven and controlled in many different ways. In the particular arrangement shown, to which my invention is not to be limited 20 or restricted, said disk is mounted upon the end of a shaft and secured thereto to rotate therewith as indicated at 60. This shaft 19 extends into a hub portion 40' forming part of an extension 40 of the frame work 25 of the machine, which constitutes a housing for the drive wheel 59. The other end of shaft 19 is journaled in a bearing 20. A gear wheel 18 is mounted to revolve loosely upon shaft 19 and is driven in any suitable 30 manner from a convenient source of power, for instance, from a motor 11 through the intermeshing gears 12, 13, respectively mounted on the motor shaft and a counter shaft 14, the latter mounted in bearings 15, 35 16, and carrying a pinion 17 which meshes with and drives the gear 18. Suitable clutch devices are employed for coupling shaft 19 to rotate with gear 18. A simple clutch arrangement is shown for this purpose 40 wherein pins 22 are carried by the gear 18, which pins in the arrangement shown are positioned at diametrically opposite points with respect to said gear, and each is provided with a portion 21 which projects beyond 45 one of the faces of said gear. A member 23 is fixed upon to rotate with shaft 19 adjacent the gear 18 and a latch member 25 is carried by the clutch member 23. This latch member is formed with an extension 50 24 formed with a bevelled shoulder and projecting towards the gear 18 to engage one or the other of the projecting portions 21 of the pins 22. The clutch latch 25 may be normally held in position for the projecting 55 portion 24 thereof to extend into the path of and to engage a projecting portion 21 of one of the pins 22. To accomplish this a simple arrangement is shown wherein the latch member 25 is formed with a shank 60 which extends into a slot or opening in the member 23 and a spring 27 interposed between a retainer plate 26, and the inner end of the latch 25 normally exerts its tension to project the latch 25 outwardly away from the member 23 and towards the gear 18 and into

position for the extension 24 thereof to engage the head or projection 21 of the pins 22. The clutch latch 25 may be moved into retracted position so as to clear the portions 21 of the pins 22 whenever it is desired to 70 arrest the rotations of shaft 19. This may be accomplished in many different ways. A simple arrangement is shown wherein a control lever 28 is pivotally mounted upon the frame work as indicated at 30 and is formed 75 with a treadle portion 29 conveniently arranged to be manipulated by an attendant of the machine. The other end of said lever is connected by means of a link 31 to one end of a lever 32 pivotally mounted in a convenient bracket 35 and having its free end indicated at 36 suitably bevelled and arranged to be projected into position to engage the extension 24 of the latch 25 in the course of rotation of the member 23, thereby forcing the latch 25 into its seat or opening in said member and against the action of spring 27, thereby causing the latch member 25 to be cleared by the extensions 21 of the pins 22 of the continuously rotating gear 90 18, permitting said gear to continue to rotate without imparting its rotations to the shaft 19 and consequently arresting the action of the punches. The lever 32 is normally held 95 in position for the free end 36 thereof to engage the projection 24 on the latch member 25 by means of a spring 34 connected to said lever. A spring 94 connected to the foot lever 28 aids in serving the same purpose. When, however, the foot lever 28 is depressed against the action of spring 94, thereby 100 rocking lever 32 against the action of spring 34, the end 36 of lever 32 is withdrawn, and thereupon the driving power is coupled to shaft 19, and hence the punching 105 devices are power actuated to their work.

The various working parts may be mounted on any suitable arrangement of framework having the features above indicated. A simple arrangement is shown including a 110 base plate 10 upon which the motor, counter shaft 14, and shaft 19, and their gearing connections, are mounted. The punching devices, work holder, and clamping devices are mounted upon a standard 42, suitably 115 secured upon the base plate.

It is believed that the operation of the machine will be fully understood from the foregoing description. The work to be punched is placed in position upon a supporting arm 46 or 54, as the case may be, and resting upon the work support 80, and in case of an irregularly shaped stamping which is flanged at its edges, where the holes are to be punched in edge flanges of the stamping, said flanges are engaged over the dies 81 of the work support, these dies being out of line with each other. The work is clamped into position by the clamping devices and the attendant then depresses 125 130

the foot lever 28. Thereupon the punches are advanced on opposite sides towards the work to accomplish their function. It will be observed that the punches are engaged 5 in gangs, one gang of punches operating in a different plane from the other gang of punches with reference to the plane defined by the base of the work support. The power connections through which the punches are 10 operated are instantly arrested when the foot lever 28 is released, without, however, arresting the continuous action of the driving motor.

While I have shown and described my invention for use in connection with punching holes in the edge flanges of sheet metal stampings for use in the construction of automobile bodies, and particularly in stampings of irregular shape, it is obvious that the 15 machine may be employed for punching holes in other stampings, and for stampings for other uses and purposes. I do not desire therefore to be limited or restricted in respect to the use to which such stampings 20 are to be employed, nor to the particular character of stampings. It will also be observed that many changes and variations in the details of construction and arrangement 25 would readily occur to persons skilled in the art and still fall within the spirit and scope 30 of my invention. I do not desire therefore to be limited or restricted to the particular construction and arrangement of parts shown and described.

35 Having thus described my invention, what I claim as new and desire to secure by Letters Patent is:

1. A machine of the class described comprising the combination of a work-support 40 having a plane surface on which the work rests, a die mounted in the side-wall of said work-support, and a punch cooperating with said die and mounted to reciprocate in a direction perpendicular to said side wall.

45 2. A machine of the class described comprising the combination of a work-support having a plane surface on which the work rests, a die mounted in the side-wall of said work-support, a block slidably mounted to reciprocate in a direction perpendicular to said side wall, and a plurality of punches 50 mounted in said block and cooperating with said die to perforate flange portions of the work.

55 3. A machine of the class described comprising the combination of a work-support having a plane surface on which the work rests, a die carried thereby, a slidably mounted block, a punch carried thereby and co- 60 operating with said die, a toggle linkage connected, at one end, to a fixed abutment and, at the other end, to said block, and means acting on said linkage to reciprocate the block in a direction substantially parallel to said surface.

4. A machine of the class described comprising the combination of a work-support, a die mounted in the side wall of said work-support, a block slidably mounted to reciprocate in a straight line perpendicular to said side wall, a punch carried by said block and cooperating with said die, a toggle linkage connected, at one end, to a fixed abutment and, at the other end, to said block, and means acting on said linkage to reciprocate said block. 70

5. A machine of the class described comprising the combination of a work-support, a die carried thereby, a slidably mounted block, a punch carried by said block and cooperating with said die, a toggle linkage connected, at one end, to a fixed abutment and, at the other end, to said block, a link 80 connected to the central pivot of said linkage, and means for reciprocating said link. 85

6. A machine of the class described comprising the combination of a slidably mounted punch carrier, a punch carried thereby, a toggle linkage connected, at one end, to a fixed abutment and, at the other end, to said carrier, a rocker arm suitably fulcrumed, a link connecting said arm and the toggle linkage, a reciprocating member to which one end of said arm is connected and means for reciprocating said member. 95

7. A machine of the class described comprising the combination of a drive shaft, a sliding member reciprocated by said shaft, a rocker arm connected to said sliding member and suitably fulcrumed, a slidably mounted punch carrier, a punch carried thereby, a toggle linkage connected, at one end, to a fixed abutment and, at the other end, to said carrier, and a link connecting said rocker arm and the toggle linkage. 100

8. A machine of the class described comprising the combination of a work-support, means for clamping the work on said support, a plurality of reciprocating punches mounted to move in a plane substantially parallel to the part of the work engaged by said clamping means, and means for reciprocating said punches. 110

9. A machine of the class described comprising the combination of a work-support having a plane surface on which the work rests, a pair of dies mounted in the opposite side-walls of said work-support, a pair of slidably mounted punch carriers, punches carried thereby and cooperating with said dies, and means for simultaneously reciprocating the punch carriers towards the work-support from opposite directions to perforate flange portions of the work. 115

10. A machine of the class described comprising the combination of a frame, a pair of posts carried thereby, a punch-carrier slidably mounted in each post, a punch carried by each punch-carrier, means for simultaneously reciprocating said punch-carriers 120

- towards each other, a work-support positioned between said posts, and dies mounted in the opposite side walls of said support and cooperating with said punches. 65
- 5 11. A machine of the class described comprising the combination of a base, a standard mounted thereon, a pair of punch-carriers slidably mounted in said standard, punches carried by said carriers, a work-support positioned between said carriers, a pair of toggle linkages, each connected, at one end, to a fixed abutment and, at the other end, to one of said punch carriers, and means acting on said linkages to simultaneously reciprocate said punch-carriers towards the work-support. 70
- 10 12. A machine of the class described comprising the combination of a base, a standard mounted thereon, a pair of punch-carriers slidably mounted in said standard, punches carried by said carriers, a work-support positioned between said carriers, a pair of toggle linkages, each connected, at one end, to a fixed abutment and, at the other end, to one of said carriers, a link connected to the center of each toggle linkage, and means for simultaneously reciprocating said links to reciprocate the punch-carriers towards the work-support. 80
- 15 13. A machine of the class described comprising the combination of a base, a standard mounted thereon, a pair of punch-carriers slidably mounted in said standard, punches carried by said carriers, a work-support positioned between said carriers, a pair of toggle linkages, each connected, at one end, to a fixed abutment and, at the other end, to one of said carriers, a pair of suitably fulcrumed rocker arms, a link connecting each rocker arm with one of said toggle linkages, and means for simultaneously oscillating said rocker arms on their fulcrums. 85
- 20 14. A machine of the class described comprising the combination of a base, a rotating shaft journaled thereon, a standard mounted on said base, a push block reciprocably mounted on said standard, operating connections between said shaft and said block, a pair of punch-carriers slidably mounted in said standard, punches carried by said carriers, a work-support positioned between said carriers, a pair of toggle linkages, each connected, at one end, to a fixed abutment and, at the other end, to one of said carriers, a pair of suitably fulcrumed rocker arms connected at one end to said block, and links connecting the other ends of said arms and said toggle linkages. 90
- 25 15. A machine of the class described comprising the combination of a work-support, a pivoted clamping member adapted to engage and clamp the work on said support, a plurality of punches, and means for simultaneously reciprocating said punches to- 65
wards the work-support. 95
- 30 16. A machine of the class described comprising the combination of a work-support, a clamping member pivotally mounted to swing into position above and clamp the work to said work-support, a plurality of punches, and means for simultaneously reciprocating said punches towards the side walls of the work-support. 70
- 35 17. A machine of the class described comprising the combination of a work-support, a clamping member pivotally mounted to swing into position above and clamp the work to said support, a toggle linkage connected to said member to lock the same in clamping position, a punch, and means for reciprocating said punch towards the work-support. 75
- 40 18. A machine of the class described comprising the combination of a work-support, a clamping member pivoted to one side of and swinging to a position above the work-support to clamp the work thereto, a lever suitably fulcrumed, a link connecting one end of said lever to said clamping member, said lever and link constituting a toggle for locking the clamping member in clamping position, a punch, and means for reciprocating the punch towards the work-support. 80
- 45 19. A machine of the class described comprising the combination of a work-support, a clamping member pivoted to one side of and swinging to a position above the work-support to clamp the work thereto, means for locking said member in clamping position, a work-engaging foot adjustably carried by said clamping member, a punch, and means for reciprocating said punch towards the work-support. 85
- 50 20. A machine of the class described comprising the combination of a work-support, a clamping member pivoted to one side of and swinging to a position above said work-support to clamp the work thereto, a gauge bar carried by said clamping member, and a punch reciprocable towards said work-support. 90
- 55 21. A machine of the class described comprising the combination of a work-support, a pair of clamping members pivoted on opposite sides of said work-support and swinging to a position above the support to clamp the work thereto, means for locking said members in clamping position, and a plurality of punches reciprocable towards the side wall of said work-support. 95
- 60 22. A machine of the class described comprising the combination of a base, a motor mounted thereon, a power shaft, connections between said motor and said shaft including a clutch operable in but one position of the shaft in its revolution, a work support carried by said base, a punch reciprocable to- 125

- wards said work-support, and mechanism actuated by said power shaft for reciprocating said punch.
23. A machine of the class described comprising the combination of a base, a motor mounted thereon, a power shaft, a brake member acting on said power shaft, driving connections between said motor and said shaft including a clutch operable at but one point in the revolution of the shaft, a work-support carried by the base, a punch reciprocable towards said support, and mechanism actuated by said power shaft for reciprocating said punch.
- 10 24. In a punching machine, a work support, in combination with means for punching holes in the work simultaneously at different distances from the plane of the base of said support.
- 15 25. In a punching machine, a work support having dies disposed at relatively different distances from the plane of the base of said support, the work engaging over said dies, in combination with punches respectively cooperating with said dies.
- 20 26. In a punching machine, a work support having dies disposed at relatively different distances from the plane of the base of said support, the work engaging over said dies, in combination with punches respectively cooperating with said dies.
- 25 27. In a punching machine, a work support, a plurality of dies mounted in the side walls of the work support at relatively different distances from the plane of the base of said support, and a plurality of punches cooperating with said dies.
- 30 28. In a punching machine, an inclined work support, a plurality of dies mounted in the side walls of said work support at relatively different distances from the plane of the base of said support, the work resting on said inclined work support and having flanges to be perforated supported thereby in front of said dies, and a plurality of punches cooperating with said dies.

In testimony whereof I affix my signature.
WALTER H. D'ARDENNE.
